(57) **CLAIM**

The ornamental design for a training wheel stabilizing device, as shown and described.

DESCRIPTION

FIG. 1 is a rear perspective view of a training wheel stabilizing device in accordance with the present invention; FIG. 2 is a front perspective view thereof; FIG. 3 is a right side elevation view thereof; FIG. 4 is a left side elevation view thereof; FIG. 5 is a top plan view thereof; FIG. 6 is a bottom plan view thereof; FIG. 7 is a front elevation view thereof; and, FIG. 8 is a rear elevation view thereof.

The broken lines in the drawings depict portions of the training wheel stabilizing device that form no part of the claimed design.
